Primary Examiner — Cathron C Brooks*Assistant Examiner* — Christopher Lee(74) *Attorney, Agent, or Firm* — Nixon & Vanderhye P.C.**(57) CLAIM**

The ornamental appearance for a forehead pad, as shown and described.

DESCRIPTION

FIG. 1 is a rear perspective view of a forehead pad according to an embodiment of our design;

FIG. 2 is a top view thereof;

FIG. 3 is a right side view thereof;

FIG. 4 is a rear view thereof; and,

FIG. 5 is a bottom view of a forehead pad according to an embodiment of our design.

Where included, broken lines showing environment or structure are for illustrative purposes only and form no part of the claimed design.
